[57] CLAIM

The ornamental design for a carrying case for audio cassettes, substantially as shown and described.

DESCRIPTION

FIG. 1 is a perspective view of a carrying case for audio cassettes, showing my new design, the opposite side not shown being identical thereto;

FIG. 2 is a front elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a perspective view in partially open position;

FIG. 8 is a front elevational view thereof;

FIG. 9 is a right side elevational view thereof;

FIG. 10 is a top plan view thereof;

FIG. 11 is a bottom plan view thereof;

FIG. 12 is a perspective view in fully extended position;

FIG. 13 is a right side elevational view thereof;

FIG. 14 is a left side elevational view thereof;

FIG. 15 is a front elevational view thereof;

FIG. 16 is a rear elevational view thereof;

FIG. 17 is a top plan view thereof; and,

FIG. 18 is a bottom plan view thereof.

The back elevation view of the FIG. 1 case as seen generally from the left in FIG. 1 is substantially the same as the FIG. 2 view.
